UNITED STATES PATENT OFFICE.

WILLIAM REID, OF KAW, OKLAHOMA, ASSIGNOR OF ONE-HALF TO WILLIAM E. VASBINDER, OF SIMMONS, TEXAS.

STOCK-CHUTE.

1,091,459.

Specification of Letters Patent. Patented Mar. 24, 1914.

Application filed July 1, 1912. Serial No. 707,041.

To all whom it may concern:

Be it known that I, WILLIAM REID, a citizen of the United States, residing at Kaw city, in the county of Kay and State of Oklahoma, have invented certain new and useful Improvements in Stock-Chutes, of which the following is a specification.

My invention relates to stock chutes, and particularly to a device of this character which is adapted to be folded into compact form when not in use.

An important object is to provide a device of this character having graded extensions on one end, so that in use, when one end of the chute rests upon one level and the other end rests upon a higher level, giving the chute an inclined position, the sides of the chute will extend as far or farther than the bottom of the chute.

A further object is to provide a device of this character which will be simple and cheap to manufacture, easy to adjust, and efficient and durable in service.

Other objects and advantages will be made apparent during the course of the following description.

Referring to the drawings forming a part of this specification, and in which like numerals are used to designate corresponding parts throughout the several views, Figure 1 is a side elevation of my improved stock chute in open position, showing it adapted for use in loading a stock car, Fig. 2 is a longitudinal section thereof showing the device adapted for use in loading a wagon from the ground, Fig. 3 is a cross section, Fig. 4 is a plan view of my device folded and adapted to be used as a wagon cover, and Fig. 5 is a cross section of it applied.

Referring more particularly to the drawings, A designates a wagon body comprising the bottom B and sides C.

D represents the doorway of a stock car, and E the floor.

My stock chute comprises a bottom section 1 of the same width as the inside of the wagon body, and hinged side sections 2 and 3. The bottom section 1 comprises longitudinal rails or bars 4, connected by strips

or slats 5. On the lower side of the bars 4 are secured other transverse bars 6, which project beyond the side bars 4 to which are secured spaced angle irons 7 whose outer faces are in alinement with the outer edges 55 of the bars 4, for a purpose to be described.

Secured along and above one side of the bottom section 1 is a longitudinal bar 8 of the same thickness as one of the side sections. To this bar is hingedly secured, as 60 at 9 the side section 2. On the opposite side of the bottom section is hingedly secured, as at 10, the side section 3.

The side sections comprise upright bars 11, to which the hinges are secured, and longitudinal strips or slats 12. It will be noted that the topmost slat projects considerably beyond the bottom 1, and the other slats terminate along the line drawn from the topmost slat to the end of the bottom section. 70

In order to hold the side sections in their proper spaced relation, I provide a bar 13 pivoted upon the upper end of a metallic strip 14 secured to one side, as shown at 15. On the other side section I provide a bracket 75 16 adapted to be engaged by the angular end 17 of the bar 13.

Any desired means may be employed to prevent the accidental displacement of the bar 13. I have shown the end 17 provided 80 with an aperture 18 adapted to aline with an opening 19 in one of the slats 12, for the reception of a pin 20. I have shown this particular locking means for purpose of illustration, but do not limit myself to this 85 structure.

In use, my improved chute is placed with one end resting inside of a wagon body, and the other end resting inside the door of a stock or other car. It will be seen that the 90 transverse projecting strip 6 on one end prevents the chute from slipping farther into the wagon body, and the strip 6 at the other end prevents the chute from being forced too far into the stock car. Owing to the fact 95 that the car floor is on a higher level than the wagon body, the chute will be inclined. By constructing the slats of the side sections longer than the bottom section, the sides project as far or farther than the bottom of the 100

chute into the car. This eliminates the gap which would result if the side slats were only as long as the bottom, and thus prevents the animals from falling or slipping off the chute.

When it is desired to use the chute for loading stock into a wagon from pens, the end of the chute at which the sides project would rest upon the bottom of the wagon, 10 and the other end would rest upon the ground preferably within a gateway.

The device is adapted to be folded by removing the pin 20, releasing the bar 17 and swinging it into the position shown in Fig. 2, 15 swinging the side 3 over upon the bottom, and then swinging the side 2 upon the top of the previously folded side. Owing to the side 2 being hinged to the bar 8, the sides will lie perfectly flat.

20 When the device is folded as described it is adapted for use as a wagon cover, the angle irons 7 engaging the inner faces of the sides of the wagon body, and the bars 6 resting upon the top of the sides, as shown

25 in Fig. 5. Of course, if it was desired, the device could be applied in the same way without being folded, and would then serve as an auxiliary body.

It will be understood that various changes 30 in the construction, proportion and arrangement of parts may be resorted to without de-

parting from the spirit of the invention, or limiting the scope of the claim.

Having thus described my invention what I claim is:

In a device of the character described comprising a platform and hinged sides, means to hold said sides in their vertical spaced relation, said means comprising a bracket mounted on one of said sides, a bar pivotally 40 mounted on said bracket and adapted to swing in a horizontal plane, a downwardly extending end formed on said bar, said downwardly extending end being provided with an aperture, a bracket mounted upon the other side portion adapted to be engaged by said end, and a pin adapted to be inserted within said aperture in said end portion and within an aligned aperture in said last named side portion, said bar being adapted to lie 50 along the top edge of said first named side portion and said end portion being adapted to lie against the adjacent end of said first named side portion when the device is in its folded position.

55 In testimony whereof I hereto affix my signature in the presence of two witnesses.

WILLIAM REID.
